UNITED STATES PATENT OFFICE.

DEMETRIUS A. HURD, OF BERTRAND, NEBRASKA.

WINDMILL.

Application filed December 12, 1922. Serial No. 606,538.

To all whom it may concern:

Be it known that I, DEMETRIUS A. HURD, a citizen of the United States, residing at Bertrand, in the county of Phelps and State 5 of Nebraska, have invented new and useful Improvements in Windmills, of which the following is a specification.

The present invention relates to wind mills, the object being to provide a mill that 10 is relatively cheap to construct, is powerful in action, and is automatically controlled so that an excessive rate of speed, with consequent injury to the mill or the machinery driven, thereby will not occur.

15 In the accompanying drawings:

Figure 1 is a side elevation of the preferred embodiment of the invention,

Figure 2 is a top plan view of the same,

20 Figure 3 is a plan view of the deck and collar,

Figure 4 is a vertical sectional view through the spider and collar, showing the mounting of the shaft,

25 Figure 5 is a detail perspective view of the outer end portion of one of the carrier arms and the blades thereon,

Figure 6 is a side elevation of the same, with the blade bearings in section.

30 Figure 7 is a perspective view of the outer end of one of the arms and the supporting bracket for the vertical spindle thereof,

Figure 8 is a detail sectional view of the 35 lower end of one of the spindles and the adjacent portion of the blade thereon,

Figure 9 is a plan view of the spider.

In the structure disclosed, concrete bases 10 support upwardly converging posts 11, the upper ends of which are connected by 40 brackets 12 with a deck 13. A vertical shaft 14 has a step bearing 15 on a concrete base 16, and has fixed thereto a collar 17 rotatably mounted in the deck.

The shaft 14 projects above the deck and 45 has secured to its upper end a spider 18 having radial extensions 19. Secured to these extensions are arms 20 disposed radially to the shaft and rotatable therewith. The outer ends of these arms are connected by stay rods 21. A rotatable carrier or 50 driving member is thus produced.

Secured to one side of the outer end of each of the arms 20 is a bracket 22, in which 55 is mounted a vertical spindle 23 that extends above and below the arm. This spindle has a flange 24 between its ends that rests upon

the bracket. It is also provided at its lower end with a supporting nut or flange 25. A set of propeller blades 26 and 27 is carried by each arm, each of said blades being preferably of sheet metal formed at one end with a sleeve 28 that receives the upper or lower end of the spindle. The blades are thus free to swing on the spindles 23 as pivots, the arms 20 being out of the paths of said 65 blades.

An abutment latch is employed for each set of blades 26—27, and consists of a lever 29 pivoted, as shown at 30, on the arm 20. One end of this lever is provided with a vertical bar 31, having offset abutments 32 located above and below the arm 20, and normally disposed in the path of the blades 26 and 27 carried by said arm. A spring 33, coiled about the pivot 30 and bearing 70 against the bar 31, serves to yieldingly urge the latch to a position with the abutments 32 behind the blades. The lever also has an outstanding arm on the opposite side to the bar 31, which lever is provided with a 75 releasing weight 34. The latch bars 31 have secured to them cords or cables 35, which extend through openings 36 in the collar 17, said cords or cables having their lower ends suitably secured to the shaft 14, 80 the shaft preferably carrying a cleat or other fastener 37 for the same.

Each of the upper blades 27 has a keeper 85 in which is pivoted a vertically suspended rod 39 that bridges the space between the 90 blades and overlaps the lower blade.

In operation assuming the latch abutments in their active positions, it will be evident that when wind is blowing, as for example in the direction of the arrow in 95 Figure 2, the blades on the left hand side will be held by the abutments of the latches, so that said blades will cause the rotation of the mill and the shaft 14. The blades on the right hand side, however, are free to 100 swing rearwardly so as to afford little resistance to this rotary movement. Should a high wind occur that would cause the mill to rotate at an excessive speed, the weighted arms under the influence of centrifugal 105 force will swing outwardly against the action of the springs 32, and thus release the normally active blades, which would swing to the dotted position, shown at the upper end of Fig. 2. When so positioned, it will 110 be evident that the bars 39 will strike the stays 21 and consequently as the released

blades move against the wind, they will effect resistance, acting in the nature of brakes or drags upon the mill until its speed is again reduced to normal, whereupon the 5 springs 33 will react to bring the latches into their normal positions, thus again bringing the blades into operation. Power may be transmitted from the mill by any suitable means, in this case, a drive pulley 40 being 10 shown on the lower portion of the shaft.

From the foregoing, it is thought that the construction, operation, and many advantages of the herein described invention will be apparent to those skilled in the art, with- 15 out further description and it will be understood that various changes in the size, shape, proportion and minor details of construction may be resorted to without departing from the spirit or sacrificing any of the 20 advantages of the invention.

What I claim, is:

1. In an apparatus of the character described, the combination with a supporting frame, of an upright shaft journaled there- 25 in, a set of outstanding arms carried by the shaft, a plurality of upright blades pivoted on the arms, a plurality of abutment latches pivoted to the arms and having portions located normally in the paths of the blades, 30 springs for yieldingly holding said latches in said paths, and weighted outstanding arms carried by the latches and operating by centrifugal force to swing the latches

out of the paths of the blades when the shaft and arms rotate at excessive speeds. 35

2. In an apparatus of the character set forth, the combination with a rotatable carrier including radial arms, feathering blades pivoted on the arms, abutment latches for holding the respective blades in their active positions, means for moving the latches to release the blades, stays connecting the outer ends of the arms outside the blades, and means carried by the blades and abutting 40 against the stays to limit the outward swinging movements of the blades when free of the latches. 45

3. In an apparatus of the character set forth, the combination with a supporting frame, of an upright shaft journaled there- 50 in, radial arms carried by the upper end of the shaft, upright spindles mounted on the outer ends of the arms, swinging blades on the spindles above and below the arms, abutment latches on the arms that engage 55 the blades and normally hold the same in active positions, centrifugally operated weighted arms for independently and automatically swinging the latches to release the arms, stays connecting the outer ends of the arms outside the blades, and stop rods carried by the blades and abutting against the stays when the blades are released and swinging outwardly, to limit the swinging movements of said blades. 60

DEMETRIUS A. HURD.
